ADJUSTABLE LAWN SPRINKLER HEAD

Alma M. Gould and Harvey A. Gould, Burbank, Calif.

Application March 3, 1955, Serial No. 491,826

6 Claims. (Cl. 299—18)

This invention relates to a sprinkler nozzle and more particularly pertains to the nozzle head portion of the sprinkler employed in permanently installed lawn sprinkling systems.

An object of the invention is to provide a sprinkler nozzle head of the above character of the type which is especially designed to deliver a fan-shaped or semi-circular spray of water which type is more generally used in sprinklers installed adjacent the margins of sidewalks, curbs, and the like so as to sprinkle the lawn area bordering the walk or curb with minimum sprinkling of the walk or curb; the particular purpose of the invention being to equip such lawn sprinkling nozzle heads with adjustable means for varying the spread of the fan-shaped spray discharged from the nozzle whereby the lawn area watered by a particular sprinkler may be varied primarily to minimize waste of water.

Another object of the invention is to provide a spray adjusting or regulating device which is applicable to the conventional type of sprinkler nozzle head with but little alteration in the construction thereof.

A further object is to equip the spray nozzle head with a spray regulating slide plate and to provide a simple and effective means of mounting and guiding the slide plate on the nozzle head and in a manner to permit ready adjustment of the slide plate relative to the nozzle orifice and embodying a construction whereby the slide plate will be automatically held against displacement in any of its adjusted positions.

With the foregoing objects in view together with such other objects and advantages as may subsequently appear, the invention resides in the parts and in the combination, construction and arrangement of parts herein-after described and claimed and as illustrated by way of example in the accompanying drawing in which:

Fig. 1 is a plan view of the sprinkler nozzle head showing the spray regulating slide plate applied;

Fig. 2 is a view in vertical section taken on the line 2—2 of Fig. 1 and indicating in dotted lines the manner of adjusting the spray regulating slide plate;

Fig. 3 is a plan view of the nozzle head with the slide plate removed;

Fig. 4 is a perspective view of the slide plate showing it detached;

Fig. 5 is a detail in section and elevation taken on the line 5—5 of Fig. 2 as seen in the direction indicated by the arrows;

Fig. 6 is a diagram in plan depicting the application of the invention;

Figs. 7 and 8 are diagrams in section showing comparative throws of streams from a nozzle afforded by adjustment of the regulating slide plate; and

Fig. 9 is a detail in section taken on the line 9—9 of Fig. 2 showing the manner in which the side margins of the slide plate are frictionally engaged with the nozzle head to hold the slide plate against displacement in its adjusted positions.

Referring to the drawings more specifically A indicates

2

generally the nozzle head of a sprinkler which head is adapted to be screwed into a tubular sprinkler coupling B connected to a suitable source of water supply under pressure; the plug being formed with the usual external threads C, a hexagonal flange D, a flat top surface E, a semi-circular dished recess F leading inwardly from a marginal portion of the flange D and having a vertical back wall G, and into the bottom of which recess F leads the nozzle orifice H adjacent said back wall. The top surface E extends on a plane spaced above flange D.

In carrying out the present invention the vertical wall D is continued on a vertical plane above the plane of the margin of the recess F and intersects the surface E perpendicular thereto. The vertical face of the wall G is flat throughout and extends transversely of the plug A contiguous the rear margin of the upper end of the nozzle orifice H.

The essence of the invention resides in equipping the nozzle head A with a spray regulating slide plate 7 and providing an adjustable mounting therefor. The plate 7 slidably seats on the surface E and is formed with an arcuate forward end portion which is designed to be projected a selected extent from the wall G to overlie the nozzle orifice H and the recess F in spaced relation thereto as shown in Fig. 2.

As a means of slidably mounting and guiding the plate 7, a diametrically extending slot 9 is formed in the upper face of the nozzle head which leads to an enlarged bore 10 extending inwardly from the margin of the flange D as particularly shown in Fig. 3, and the slide plate 7 is formed with a downturned stem 11 which projects through the slot 9 and is formed with an end enlargement 12 which projects into and slidably fits the bore 10.

As a further means of mounting and guiding the slide plate in a seated position on the top surface E of the nozzle head, the opposed side margins of the slide plate are formed with downwardly extending parallel flanges 14—14 having inturned tongues 15—15 which are slidably and frictionally engaged in grooves 16—16 formed in the opposite sides of the sprinkler head adjacent the surface E and paralleling the latter. The flanges 14—14 in extending astride the sprinkler head in close proximity thereto serve to hold the slide plate against lateral displacement, and the tongues 15—15 in snugly fitting the grooves 16—16 serve to hold the slide plate against upward tilting under the impact of the stream of water discharging through the nozzle orifice H against the underside of the forward projecting portion of the slide plate.

By the recited construction the slide plate 7 may be shifted diametrically of the nozzle head A perpendicular to the wall G so as to vary the extent of projection of the arcuate forward end portion 8 of the plate 7; the enlargement 12 on the stem 11 in engaging the walls of the bore 10 and the tongues 15—15 frictionally engaging the grooves 16—16 serving to hold the slide plate 7 in place in any of its adjusted positions.

In the operation of the invention the overhanging end portion of the slide plate 7 serves to deflect the stream of water delivered upwardly through the nozzle orifice H and to direct a fan-shaped spray from one side of the nozzle head, the spread of which may be varied according to requirements by adjustment of the slide plate 7. Manifestly the less the overhang of the forward portion 8 of the slide plate 7 beyond the wall G and nozzle orifice H, the higher and shorter will be the trajectory of the spray and conversely the greater the extent of such overhang of the slide plate the lower and longer will be the trajectory.

It is contemplated that once the slide plate is adjusted to produce the desired trajectory of the spray no further adjustment will be required, but manifestly in event it

may become necessary or desirable to change its position it is only necessary to shove the slide plate forward or back within the range of its movement to whatever position will give the wanted result.

While a specific embodiment of the invention has been shown and described, it is not limited to the exact construction set forth, but embraces such changes and modifications as come within the meaning and scope of the appended claims.

We claim:

1. In a sprinkler nozzle head having a flange formed with a flat upper face formed with a semi-circular dished recess having an upstanding back wall extending above said face, said head having an upper flat surface leading from said back wall on a plane above the flat upper face of said flange, said head being formed with an upwardly opening water discharge orifice leading through the bottom of said recess, a slide plate having a flat face seated on said surface and having an outwardly curved arcuate forward marginal portion protruding over said recess from the upper edge of said back wall, a cylindrical bore leading into said nozzle head from a side thereof, said upper surface being formed with an open ended channel opening downwardly to said bore, and means on said slide plate frictionally engaging said bore adapted to hold said slide plate in various adjusted positions relative to said back wall.

2. The structure called for in claim 1 in which said guideway engaging means embodies a stem on said slide plate extending through said channel, and an enlargement on said stem arranged in said bore in sliding contact with the nozzle head.

3. In a sprinkler nozzle head having a flange formed with a flat upper face formed with a semi-circular dished recess having an upstanding back wall extending above said face, said head having an upper flat surface leading from said back wall on a plane above the flat upper face of said flange, and said nozzle head being formed with an upwardly opening water discharge orifice leading through the bottom of said recess, a slide plate having a flat face seated on said surface and having an outwardly curved arcuate forward marginal portion protruding over said recess from the upper edge of said back wall, parallel grooves on opposite sides of said nozzle head, tongues on opposed margins of said slide plate engaging said grooves, a cylindrical bore leading into said nozzle head from a side thereof and an open ended channel in said upper surface opening downwardly to said bore, and means on said slide plate engaging said bore adapted to hold said slide plate in various adjusted positions relative to said back wall.

4. In a sprinkler nozzle head having an upper flat surface and formed with a flange having semi-circular recess having an upstanding back wall and said nozzle head being formed with an upwardly opening water discharge orifice leading through the bottom of said recess, a slide plate having a flat face seated on said surface and having a forward marginal portion protruding over said recess from the upper edge of said back wall, said nozzle head being formed with parallel grooves on opposite sides thereof, side flanges on said slide plate overlying said opposite sides of said head holding said plate against lateral movement on said head, tongues on said flanges projecting into said grooves holding said plate against upward movement relative to said head, a cylindrical bore leading into said nozzle head from a side thereof and an open ended channel in said upper surface opening downwardly to said bore, a stem on said slide plate extending through said channel, and an enlargement on said stem arranged in said bore in sliding contact with the nozzle head.

5. In a sprinkler nozzle, a head formed with a flange having an upper flat surface formed with a semi-circular dished recess having an upstanding flat back wall continuing on a vertical plane above the plane of the margin of said recess, said head having a flat top surface extending on a plane spaced above said flange, said back wall intersecting said top surface perpendicular thereto, said head being formed with an upwardly opening water discharge orifice leading through the bottom of said recess adjacent said back wall; a slide plate slidably seated on said top surface formed with an outwardly curved arcuate forward end portion adapted to be projected a selected extent forward of said vertical wall to overlie said nozzle orifice and the dished recess in spaced relation thereto, and means for guiding said slide plate on said head and for holding it against tilting relative thereto.

6. The structure called for in claim 5 together with means fixed on said slide plate slidably and frictionally engageable with said head for holding said slide plate in various adjusted positions thereon relative to said back wall.
